UNITED STATES PATENT OFFICE.

RUFUS J. HUTCHINS AND JOHN KIRBY, JR., OF DAYTON, OHIO, ASSIGNEES TO THE DAYTON MANUFACTURING COMPANY, OF DAYTON, OHIO, A CORPORATION OF OHIO.

WATER HEATER.

1,414,361.

Specification of Letters Patent.

Patented May 2, 1922.

Application filed October 4, 1919. Serial No. 328,561.

To all whom it may concern:

Be it known that we, RUFUS J. HUTCHINS and JOHN KIRBY, Jr., citizens of the United States, and residents of Dayton, in the county of Montgomery and State of Ohio, have invented certain new and useful Improvements in Water Heaters, of which the following is a description, reference being had to the accompanying drawings, which

10 form a part of our specification.

Our invention relates to improvements in water heaters of the type adapted to domestic purposes.

Our invention has for its objects to provide improved means for supporting the outer casing for the heater upon the heating unit within the same; whereby the casing may be rotated on its support and fixed at any desired angle relative to the heating unit or exterior attachments, to provide means for deflecting heat generated by a burner, located at the lower end of the casing toward the center of the heating unit, and to provide improved means for connecting the tubes of the heating unit with the heads thereof, together with other objects which will be disclosed in the specification.

With the aforesaid objects in view the invention consists in the novel construction hereinafter fully described in the specification, illustrated in the drawings and more particularly pointed out in the claims.

In the accompanying drawings forming part of the specification; Figure 1 represents the complete heater, in elevation, with its hinged door section open and showing the heating unit and the burner in their respective positions; Fig. 2 is a horizontal section taken through the line X X of Figure 1; Fig. 3 is an enlarged broken sectional view of the upper and lower headers showing the manner in which the tubes are connected therewith, and Fig. 4 is a view in elevation, of the heating unit, the casing being removed.

In the said drawings,

A represents a heating unit comprising a series of tubes 1, joined at their ends to upper and lower headers, 2—3, the upper header comprising a base section 2' and a tube section 2'', and the lower header comprising a base section 3' and a tube section 3'', sections 2' and 3' are each provided with an

annular shoulder 4'—4'' against which when the sections are screwed together the upper edge of the vertical rim of the respective sections, 2''—3'', impinges, thus forming a water tight joint, as shown in Figure 3, and when the sections are assembled for service they form chambers 5—6, the said tubes being located near the peripheral walls of the headers.

This heating unit is attached, at 7, to and is supported in an upright position by a supply pipe 8 leading from and connecting with a tank from which water flows into the chamber 6, thence upwardly through the tubes 1 into the chamber 5 and outwardly therefrom through a tubular extension 9, which in the present instance is shown formed integral with the section 2' of the header 2 and to which is connected a discharge pipe leading back into the supply tank, from which tank the hot water is drawn in the usual manner.

To expedite assembling the headers, there is formed thereon hexagon portions 10, 11 to accommodate a wrench, by the use of which the header section may be screwed tightly together, in the top end of the portion 10 there is formed an annular recess 12 and the tubular extension 9 is screw threaded to receive an adjustable nut 13 provided with a corresponding recess 14.

A two-part casing B—B', separated through its center vertical line and hinged together, as shown at 15—15', is held in closed position by means of suitable catch devices, such, for example, as are shown at 16, 17, the upper end of the part B terminates in a semi-annular vertical flange or collar portion 18 which extends above and below the point of union with said part B and fits over or around the tubular extension 9 with its lower end resting on the bottom of the recess 12, thus the casing is supported in a suspended position around the heating unit and can be set in any position to permit of the door or B' part of the casing being opened at any desired angle relative to surrounding objects, and when so set and the nut 13 is screwed down until the bottom of the recess 14 bears hard against the upper end of the collar portion 18 part B will be maintained in a fixed position regardless of whether the door section is open or closed,

the upper end of part B' or door half of the casing being cut away at 19 to receive the extension member 9 and permit the door to close. At the bottom of the casing, which is 5 open, and therewithin, there is located a heat generating element, or burner C having connection with a source of fuel supply and being provided with a laterally disposed flange 20, which engages a groove 21 formed 10 on the inside of the stationary or B portion of the casing, the said flange being provided with openings, not shown, for the admission of air into a combustion chamber hereinafter described.

15 In order to obtain the most efficient result in the utilization of heat generated by the burner the distance from the face of the burner to the bottom of the heating unit is an important factor and which in our im- 20 proved heater, as above described, is estab- lished and maintained through the fixed location of the burner in the casing and the collar portion 18, at the upper end of the casing, resting in the recess 12 at the 25 top of the header 2, which latter con- struction performs the dual function of sup- porting the casing over and around the heating unit and controlling the distance be- 30 tween the face of the burner and the bottom of the unit, thus avoiding inefficient opera- 35 tion of the heaters through carelessness or ignorance on the part of those intrusted with their installation.

Another important factor in the efficiency 40 of water heaters of the class to which the present invention belongs lies in the form and dimensions of the casing relatively to the heating unit, and in order to obtain proper combustion and to utilize the heat generated by the burner to the best advan- 45 tage in heating the water as it flows through the heating unit, the lower part of the casing is enlarged to form a combustion chamber D, within which the flame from the burner mixes with air, admitted in regulated quan- 50 tity into the chamber through suitable open- 55 ings formed in or around the burner, the diameter of the casing at a point slightly above the header 3 being reduced to a degree which while not tending to impede the pas- 60 sage of the products of combustion upward confines the same to a reduced area and dis- tributes the heat more effectively between 65 and around the heating unit. The upper end of the casing also is enlarged to allow for free escape of the heat products into a flue-pipe 22 by which the same are carried into the outer atmosphere.

On the inside of the casing and spaced 60 apart therefrom there is located, within the chamber D, a deflector E, which may be se- 65 cured to the casing by means of bolts or rivets 23, or by other suitable means, its function being to direct the heat between the tubes of the heating unit towards the

inside thereof, and also to protect this por- 70 tion of the casing from direct contact with the heat from the burner.

Heretofore, in constructing water heaters 75 of the type to which this specification re- lates it has been customary to solder the ends of the tubes to the headers in order to form water tight joints and when heat is applied to the heating unit and there is no water in the unit, as frequently happens, the 80 heat melts the solder, often causing leaky joints, necessitating repairs which are both costly and annoying. In our improved heater this serious objection is overcome by a new and novel manner of joining the tubes 85 to the headers, the same being more clearly illustrated in Figure 3 of the drawings, which show the headers partially in section with one of the tubes, also in section, fixed in position in the sections 2"-3" thereof and in which 24 represents bosses on the 90 walls 25, their purpose being to provide additional bearing surfaces for the tube ends, there being one such boss for each tube end, the ends of the tubes are formed slightly taper, as at 26, and the bossed por- 95 tions 24 of the header sections 2"-3" are provided with corresponding taper bores to receive the tube ends. In assembling the 100 heating unit the tubes, of which in the pres- ent instance there are thirteen and which number may be increased or diminished, are first arranged with one end of each tube engaging one of the taper bores of either 105 of the sections 2" or 3", the other of the 110 said two sections is then similarly placed in position on the opposite ends of the tubes when by the application of pressure the said taper surfaces of the tubes and the header sections are forced into water tight connec- 115 tions and the joints thus established held against disturbance by lapping the ends of the tubes over the inner side of the walls 25, preferably into a countersink formed therein as shown at 27 in said Figure 3.

If the heating element comprised two or more rows of tubes in its construction the flow or passage of water through the tubes from the bottom to the top header would have a tendency to pass in greatest quan- 120 tity through those tubes directly over, or nearly so, the inlet water supply pipe at- 125 tached to the bottom header.

Assuming the heater is connected to city 120 pressure and cold water only is drawn through the heater and out of a faucet at- 125 tached to the outlet of the heater, it is nat- 130 ural there would be a flow through all the tubes but it is equally natural that the greatest flow would be through the tubes directly over or contiguous to the inlet supply pipe. When water under pressure enters such con- 130 structed apparatus, if the apparatus is sealed at its outlet the pressure of the water is equal in each tube; but upon opening the

outlet the pressure is increased on the central or inner tubes and therefore the passage of water in greatest volume is through the inner tubes. It is realized that at one and 5 the same time water is passing through all of the tubes.

Connect this heating element in position to city water and a storage tank, apply heat as in the heating of a gas tank water heater, 10 and the water heated in the heating unit is hottest in the tubes nearest the periphery of the header. It is obvious these tubes get the first call on the heat and being more directly exposed to the action of the heat a more 15 rapid rise or passage of the heated water through the outer tubes than the inner or cooler tubes. It will be borne in mind that while cold the heater is under water pressure, that is to say, equal pressure is being 20 exerted through all parts of the heater, yet the moment heat is applied the pressure equation is instantly changed as hereinabove mentioned. Moreover, by placing a multiple of rows of tubes in the element excessive 25 condensation would result.

By employing preferably one row of tubes, specifically located as hereinabove described, several things are accomplished, among 30 which are: an equal efficiency in the apparatus; a great saving in material and labor in construction; greater stability of construction; and a reduction in condensation and its attendant deleterious effects on the tubing.

To install the heater, the heating unit is 35 first attached to the water supply pipe in an upright position, as shown in Figure 4, the casing is then mounted upon and secured to the heating unit in the desired position, as before explained, the burner is then placed 40 in position within the casing, to which it may be secured by any suitable means, none being shown, after which the burner is connected up with the fuel supply and when the proper water connections are made the 45 heater is ready for service.

We claim:

1. In a water heater, in combination, a heating unit, a water supply pipe connected therewith and constituting a support therefor, a 50 casing comprising two sections hinged together adapted to inclose said unit; one of said sections having a vertically disposed flange member at the upper end thereof which engages an annular recess formed in said unit, a threaded extension projecting upwardly from said unit, and a nut operative on said extension having an annular recess formed in the under side thereof to engage the upper end of said flange member; 55 whereby the casing is supported in a suspended position upon and wholly by said unit.

2. In a water heater, in combination, a heating unit comprising a series of vertically 60 disposed tubes having their ends connected

with upper and lower headers forming enlarged chambers with which said tubes communicate, an exteriorly screw threaded member extending upwardly from the upper of said headers, an annular recess formed in 70 said upper header near the base of and surrounding the said member, a casing inclosing said unit provided with a vertically disposed integral member extending above and below its point of union with the casing 75 and adapted to engage and rest in said recess, an interiorly screw threaded nut operative on said upwardly extending member and having an annular recess formed in the under side thereof adapted to engage the upper end of said integral member and to secure the same firmly in said recess; whereby the casing is supported in a suspended position upon and wholly by said unit. 80

3. In a water heater, in combination, a 85 heating unit comprising a series of vertically disposed tubes having their ends connected with upper and lower headers forming enlarged chambers with which said tubes communicate, an exteriorly screw threaded member extending upwardly from the upper of said headers, an annular recess formed in said upper header near the base of and surrounding the said member, a casing inclosing said 90 unit provided with a vertically disposed integral member extending above and below its point of union with the casing and adapted to engage and rest in said recess, an interiorly screw threaded nut operative on said upwardly extending member and having an annular recess formed in the under side thereof adapted to engage the upper end of said integral member and to secure the same firmly in said recess; whereby the casing is supported in a suspended position upon 95 and wholly by said unit, a water supply pipe connected with said unit and constituting a support therefor, and means located below said unit for generating heat within said casing. 100

4. In a water heater, in combination, a heating unit comprising a series of tubes joined to upper and lower headers, an outlet member extending upwardly from the upper of said headers, a recess formed in said 115 header at and around the base of said outlet member, an adjustable nut operative on said outlet member above said recess and having a corresponding recess formed in the under side thereof, a casing inclosing said unit and suspended therearound by means of a vertically disposed flange member formed thereon at the top end thereof and engaging the said recesses. 120

5. In a water heater, a heating unit, a 125 supply pipe connected with and constituting the support for said unit, a casing comprising two longitudinal sections hinged together; said sections when closed forming an inclosure for said unit and a combustion 130

chamber therebelow; one of said sections having a vertically disposed flange member at the upper end thereof which engages an annular recess formed in said unit, a threaded extension projecting upwardly from said unit, and a nut operative on said extension having an annular recess formed in the under side thereof to engage the upper end of said flange member; whereby the casing 10 is supported in a suspended position upon and wholly by said unit, in combination with a heat generator located in said chamber.

6. A new article of manufacture comprising a casing for water heaters consisting 15 of two longitudinal sections hinged together adapted to incase a heating unit, one of said sections having at its upper end a vertically disposed integral member extending above and below its point of union with the casing and adapted to engage a fixed and a movable annular recess at the upper end of the heating unit and to support the casing in suspended position upon said unit; and the other of said sections being adapted to 20 be opened to afford access to said unit and when closed to cooperate with said first mentioned section in forming an inclosure therefor.

7. In water heater construction, a heating 30 unit comprising upper and lower headers each consisting of two peripherally threaded sections screwed together to form a chamber and a series of vertically disposed tubes united at their respective ends to said headers and communicating with said chambers; one section of each header being formed 35 with an annular shoulder against which the outer vertical rim of the other section impinges; tapered holes extending through the horizontal wall of each header provided 40 with countersinks on one side thereof; said tubes having corresponding tapered ends which extend through said holes and are held firmly therein by flanging their free ends 45 outwardly in said countersinks over one section of each header on the inside of their respective chambers.

8. In a water heater, in combination, a heating unit comprising a series of vertically arranged tubes joined to upper and lower headers, an exteriorly threaded outlet member extending upwardly from the upper of said headers, an annular recess formed in said upper header at the base of 50 said outlet member, an adjustable nut operative on said outlet member and having an annular recess formed in the under side thereof, and a casing inclosing said unit and

suspended therearound by means of a vertically disposed flange member formed thereon and engaging the said recesses. 60

9. A new article of manufacture comprising a header for water heating units consisting of a base section and tube section; said base section terminating in a vertically disposed exteriorly screw threaded rim having an annular shoulder adjacent thereto; and said tube section consisting of a horizontally disposed disk-like member terminating in a vertically disposed interiorly screw 65 threaded rim registering and adapted to couple with said first mentioned rim and to seat against said shoulder; the two sections when coupled together forming a chamber, said tube section being provided with a 70 series of tube-bosses located on one side of said disk-like member and having tapered perforations extending therethrough into said chamber and adapted to receive tubes having correspondingly tapered ends and 75 comprising a feature of said water heating unit, said tapered perforations being provided with reverse countersinks into which the free ends of the tubes may be flanged 80 outwardly over one section of each header 85 on the inside of their respective chambers.

10. In water heater construction, a heating 90 unit comprising upper and lower headers which form chambers and a series of vertically disposed tubes united at their respective ends to said headers and communicating with said chambers, each of said headers consisting of a base section having a vertically disposed screw threaded circumferential member and an annular shoulder 95 adjacent thereto; and a tube section comprising a horizontal wall terminating in a vertically disposed screw threaded member adapted to engage said first mentioned member and to impinge said shoulder, said horizontal wall being provided with a series of boss members having tapered perforations which 100 extend through said wall, and which are provided with reverse countersinks formed in the wall opposite the said bosses, the ends of said tubes being correspondingly tapered 105 and engaging said perforations; the tubes being held firmly therein by flanging their free ends outwardly in said countersinks over the tube section of each header on the inside 110 of their respective chambers.
